UNITED STATES PATENT OFFICE.

LEWIS G. ROWAND, OF CAMDEN, NEW JERSEY, ASSIGNOR TO THE UNIVERSAL FIRE ALARM COMPANY, OF SAME PLACE.

AUTOMATIC SAFETY DEVICE FOR ELECTRIC CIRCUITS.

SPECIFICATION forming part of Letters Patent No. 542,030, dated July 2, 1895.

Application filed February 6, 1895. Serial No. 537,444. (No model.)

To all whom it may concern:

Be it known that I, LEWIS G. ROWAND, a citizen of the United States, residing at Camden, county of Gloucester, and State of New Jersey, have invented a new and useful Improvement in Automatic Safety Devices for Electric Circuits, of which the following is a full, clear, and exact description, reference being had to the accompanying drawings, which form a part of this specification.

My invention consists, essentially, in placing upon an electric circuit at the commencement of said circuit a switch controlled by an electric device, preferably an electromagnet, in shunt with the circuit upon which is the switch, the resistances of the shunt-circuit being greater than the resistance of the line-circuit under normal conditions; but if a wire breaks in the main circuit the resistance becomes greater than the resistance of the shunt-circuit and the magnet is energized, so that it acts upon the switch to open the line or circuit at its commencement, so that the broken wire is no longer a live wire.

My invention is adaptable to all character of circuits, either light or power, and is especially applicable for use in electric roads, as will hereinafter be fully pointed out.

Figure 1 is a diagrammatic view showing my invention applied to a single circuit. Fig. 2 is a vertical longitudinal section of switch and controlling device. Fig. 3 is a plan of single switch and switch-controlling device, gearing omitted. Fig. 4 is a plan of double switch and switch-controlling device, gearing being shown. Fig. 5 is a side elevation showing position of and support for switch-box. Fig. 6 is a diagrammatic view showing my invention applied to an electric railway with sub-sections in main section. Fig. 7 is a diagrammatic view showing my invention applied to a multiple circuit. Fig. 8 is a diagrammatic view showing my invention applied to a number of main electric-railway sections. Fig. 9 is a diagrammatic view of double switch and connections. Fig. 10 is a diagrammatic view of single switch as used in Fig. 8. Fig. 11 is a diagrammatic view of single switch as used in Fig. 6. Fig. 12 is a diagrammatic view showing signaling devices

and electrical connections used with switch devices.

Fig. 1 represents a circuit B, in which D is the dynamo, and D' a lamp in the circuit. At a point close to the commencement of the circuit I insert the device X, (shown in Figs. 2 and 3,) Fig. 2 being a section, and Fig. 3 a plan. In this device A is a switch-lever pivoted at a, and at the pivoted end, by means of the binding-post a', connection is made with the wire of the main circuit. The other end of lever A rests against a spring-contact b, connected to the binding-post b', with which the wire of the main circuit beyond the switch is connected. Therefore, when the lever A is in contact with spring-contact b, the circuit is complete through the switch. The switch-lever stands vertically and is normally held against the contact b by means of the catch c on the pivoted arm C engaging a projection b² from the lever. The pivoted arm C carries the armature of a magnet E, the catch holding the lever when the armature is unacted on by the magnet. The magnet E is in shunt with the main circuit. The resistance of the magnet E is greater than the resistance in the main circuit B, and consequently normally the magnet is not energized, and the catch of armature holds the lever in position against the contact b and the circuit is active on the line. If by any reason the wire of circuit B should break, the resistance in the line will at once become greater than the resistance of the shunt-circuit, and the magnet E will become energized and the armature C drawn in, releasing the catch from lever A, and the lever will fall, opening the main circuit at its commencement, and the broken wire will no longer be a live wire.

If the circuit be a multiple circuit, as shown in Fig. 7, then the device X is preferably placed at each circuit of the multiple. Thus I place one at 1, contiguous to the dynamo. I place one at the branch 2, contiguous to the point of departure from the main line. I place one on the main line just beyond this branch 2, that being the commencement of a new circuit which extends to the branch 3, and at the commencement of this branch 3 I place a similar device, and so on throughout.

Each circuit of the multiple where it commences is provided with a device, such as before described, so that, if in any of these circuits a wire is broken, the current is cut off 5 from passing through the circuit in which the wire is broken, so that there is no danger of live wires. When a ground-circuit is used, I use a single switching device. (See Fig. 10.) Where there is a metallic circuit I prefer to 10 use a double switching device with two levers, one controlling the connection of one wire, the other controlling the circuit to the other wire, both levers being controlled by the armature C of magnet E, as shown in Figs. 4, 7, and 9. 15 Where in multiple circuits I use a device for each circuit and it is desired to register at the central station or power-house the circuit in which the break has occurred, so that it may be repaired, I provide the following mechanism:

Connected in series in a circuit independent of the line-circuits is a series of disks F F' F², &c., said disks corresponding in location and position and number with the devices 25 X. These disks are insulated at that portion of the periphery upon which are the insulating-strips f. (See Figs. 2, 4, and 12.) F has one strip, F' two, and F² three, and so on. f' are brushes resting upon these disks connected in series, and in the circuit at the power-house is a signal L. On the shaft f² of each of disks F F', &c., is a gear G', which meshes with gear-wheel G' and gear-wheel G². Upon the shaft of gear G² is a gear which 30 meshes with the spring-acting gear G, and fixed upon the shaft of gear G' is a disk having a notch g in its periphery, in which is adapted to rest the toe-piece h of the arm H, connected to armature C.

40 When the magnet E is energized, as before described, the movement of the armature prevents the further reception of current in the main circuit, and it also moves the toe-piece h from the notch g, allowing the spring-gear G to act, and signal is given. The number of signal is dependent upon the number of strips f. Thus, if the wire broken is in the circuit corresponding to disk F, one signal will be given; if F', two signals, and so on, so that the 45 person at the station can tell by the number of the signal the location of the break. Any other mechanism controlled by the circuit-breaker to give the signal may be used.

In practice it is preferable to make the gear 55 G' such that it will revolve once in two revolutions of disk F, so that two sets of signals may be given before the toe-piece h again engages the notch g.

I can operate the levers of switch device by 60 hand, if desirable to cut off the current from any circuit, in the following manner: J is a bell-crank, to one end of which is attached a cord j, which passes to the desired point. The other end is in alignment with armature C, so that when the string is pulled the armature is forced toward the magnet and the levers released. (See Figs. 2 and 5, in which Fig. 5

is a view of pole with controlling switch mechanism and cord extending downward to the point where it can be reached.)

As before stated, my invention is especially applicable to electric railways, and in Figs. 6 and 8 I have illustrated my improvement applied to such a use. Taking first Fig. 8, K is the dynamo; K', the trunk-line; k k' k² k³ k⁴, 70 the feed-wires leading from the line K' to the trolley wire of its corresponding trolley section l l' l² l³ l⁴. The end of each of the sections l to l⁴ is connected with the ground through resistance, which resistance is greater than that of the car-motors. In shunt with each circuit l l' l⁴, and at the point where the said circuits connect with their corresponding feed wire k l' k⁴—that is, at the commencement of each circuit of the trolley-wire—I 75 place the device X, hereinbefore described, in a shunt-circuit, (see Figs. 8 and 10,) the resistance of whose shunt-circuit magnet is greater than the motor-resistance or the trolley-section-circuit resistance, so that, so long as the trolley-wire of that circuit remains intact the magnet is not energized; but when the wire of any section is broken, its corresponding magnet is energized and the current cut off from that section of the trolley-wire. 80 As, however, the sections l l' l², &c., are of considerable length in practice, and there being also several supporting-poles in a section, a wire may break when two or more cars are in the section, and a car between the section-magnet and the break, in which case the trolley-wire of that section would still remain alike. This can be obviated by the motormen of all the cars in a section cutting out their 85 motors when the break occurs, when the magnet corresponding to said section would at once act and cut off current from the wire. However, a better method than this is shown in Fig. 6, where I form in each section l to l⁴ (one section l and a part of another l' being 90 shown) a number of shunt-circuits, such as shown in Fig. 11, each having a magnet controlling a switch upon the trolley sub-section line, so that if the break takes place anywhere in the sub-section, the distance between the 95 break and a magnet will be so short that the possibility of a car being there is remote, and if there, the time which it remains there would be short. In practice I purpose placing these 100 shunt-magnets and switches at the points where there are supporting-poles. The theory 105 of this last method (shown in Fig. 6) is that each car makes a separate circuit, and if I arrange my magnets and switches to provide for the maximum number of possible circuits 110 thus formed, I am in position to cut the current from a broken wire at any point.

The registering devices heretofore described can be used with the method shown in Figs. 6 and 8, just described, so as to indicate the location of the broken wire.

Having now fully described my invention, what I claim, and desire to protect by Letters Patent, is—

1. The combination with an electric circuit, of a normally closed switch in said circuit, an electric device in a closed shunt with said circuit and adapted to control said switch, the 5 resistance of said device being greater than the resistance of the circuit, the arrangement being such that when the resistance of the circuit is unduly increased, said device is energized and said switch is opened.
- 10 2. The combination with an electric circuit of a normally closed switch at the commencement of said circuit, an electric device in a closed shunt with said circuit and adapted to control said switch, the resistance of said device being greater than the resistance of the circuit, the arrangement being such that when the resistance of the circuit is unduly increased, said device is energized and said switch is opened.
- 15 3. The combination with an electric circuit, of a plurality of switches in said circuit, each switch being controlled by an electric device in a closed shunt with said circuit, the resistance of which device is greater than the resistance of the circuit, the arrangement being such that when any device is energized its corresponding switch is operated to open the circuit at said switch.
- 20 4. In combination with multiple electric circuits, each being provided with a normally closed switch, an electric device in a closed shunt with its corresponding circuit and controlling its corresponding switch, the resistance of each of said devices being greater than the resistance of its corresponding circuit, the arrangement being such that when any of said devices is energized its corresponding switch is operated and its circuit broken.
- 25 5. In combination with multiple electric circuits each being provided at its commencement with a normally closed switch, an electric device in a closed shunt with its corresponding circuit, and controlling its corresponding switch, the resistance of each of said devices being greater than the resistance of its corresponding circuit, the arrangement being such that when any of said devices is energized its corresponding switch is operated and its circuit broken.
- 30 6. In combination with multiple electric circuits, a plurality of switches in each of said circuits, each switch being controlled by an electric device in a closed shunt with its corresponding circuit, the resistance of each of said devices being greater than the resistance of its corresponding circuit, the arrangement being such that when any device is energized its corresponding switch is operated to open its corresponding circuit at said switch.
- 35 7. In combination with an electric circuit, a normally closed switch in said circuit, an electric device in a closed shunt with said circuit and adapted to control said switch, the resistance of said device being greater than the resistance of the circuit, the arrangement being such that when the resistance of the circuit is unduly increased said device is energized and said switch is opened.
- 40 8. The combination with an electric circuit, of a plurality of switches in said circuit, each switch being controlled by an electric device in a closed shunt with said circuit, the resistance of which device being greater than the resistance of the circuit, the arrangement being such that when any device is energized its corresponding switch is operated to open the circuit at said switch, a circuit independent of the first mentioned circuit, signaling devices equal in number to said switches, and the corresponding signaling device being adapted to be thrown into action when its corresponding switch is opened, and a receiving device in said circuit.
- 45 9. In combination with multiple electric circuits, each being provided with a normally closed switch, an electric device in a closed shunt with its corresponding circuit and controlling its corresponding switch, the resistance of each of said devices being greater than the resistance of its corresponding circuit, the arrangement being such that when any of said devices is energized its corresponding switch is operated and its circuit broken, a circuit independent of the first mentioned circuits, signaling devices equal in number to said switches, and the corresponding signaling device being adapted to be thrown into action when its corresponding switch is opened, and a receiving device in said circuit.
- 50 10. In combination with multiple electric circuits, a plurality of switches in each of said circuits, each switch being controlled by an electric device in a closed shunt with its corresponding circuit, the resistance of each of said devices being greater than the resistance of its corresponding circuit, the arrangement being such that when any device is energized its corresponding switch is operated to open its corresponding circuit at said switch, a circuit independent of the first mentioned circuits, signaling devices equal in number to said switches and the corresponding signaling device being adapted to be thrown into action when its corresponding switch is opened, and a receiving device in said circuit.
- 55 11. The combination with an electric circuit of a normally closed switch in said circuit, an electric device in a closed shunt with said circuit and adapted to control said switch, the resistance of said shunt circuit being greater than the resistance of the circuit, the arrangement being such that when the resistance of the circuit is unduly increased said device is energized and said switch is opened.

12. The combination with an electric circuit of a plurality of normally closed switches in said circuit, each switch being controlled by an electric device in a closed shunt with said circuit, the resistance of which shunt circuits being greater than the resistance of the circuit, the arrangement being such that when any device is energized its corresponding switch is operated to open the circuit at said switch.

13. In combination with an electric circuit, a normally closed switch in said circuit, an electric device in a closed shunt with said circuit and adapted to control said switch, the resistance of said shunt circuit being greater than the resistance of the circuit, the arrangement being such that when the resistance to the circuit is unduly increased said device is energized and said switch is opened, a circuit independent of the first mentioned circuit, a translating device in said circuit adapted to be thrown into action when the electric device is energized and a receiving device in said circuit.

14. The combination with an electric circuit of a plurality of normally closed switches in said circuit, each switch being controlled by an electric device in a closed shunt with said circuit, the resistance of which shunt circuits being greater than the resistance of the circuit, the arrangement being such that when any device is energized its corresponding switch is operated to open the circuit at said switch, a circuit independent of the first mentioned circuit, translating devices equal in number to said switches, and the corresponding translating device being adapted to be thrown into action when its corresponding switch is opened, and a receiving device in said circuit.

In testimony of which invention I have hereunto set my hand.

LEWIS G. ROWAND.
